[57] CLAIM

The ornamental design for a diffuser nozzle for a hair dryer, as shown and described.

DESCRIPTION

FIG. 1 is a right side elevational view of the diffuser nozzle for a hair dryer according to the present invention shown in combination with a hair dryer;

FIG. 2 is a top plan view thereof, with the bottom view being identical;

FIG. 3 is a right side elevational view thereof, with the left side elevational view being identical; and,

FIG. 4 is a front elevational view thereof.

The broken line showing of the hair dryer, including the cross-hatched pattern indicative of a black color is for illustrative purposes only and forms no part of the claimed design.
